UNITED STATES PATENT OFFICE

2,152,898

HAIR CUTTING AND SHAPING IMPLEMENT

Arthur H. Madore, San Leandro, Calif.

Application May 1, 1936, Serial No. 77,345

4 Claims. (Cl. 30—30)

My invention relates to a hair cutting and shaping implement, and the construction herein shown and described is an improvement on a somewhat similar instrument patented by me October 21, 1934, No. 1,975,328.

The principal objects of my invention are, to generally improve upon and simplify the construction of the hair cutting and shaping implement covered by my aforesaid patent, as well as other forms of similar implements, and to provide a hair cutting and shaping implement that includes a comb having two or more sets or teeth that differ in length, and to combine with said comb a pair of double edged blades, which latter cooperate with the teeth of the comb in performing various hair cutting, thinning and contouring operations.

A further object of my invention, is to provide simple and efficient means for firmly securing the double edged blades in proper position upon the comb, and which securing means is readily releasable, in order to permit the ready interchange of blades and to facilitate the cleaning of the blades and combs.

A further object of my invention is, to provide a hair cutting and shaping implement of the character referred to that includes two or more auxiliary combs that may be used for various operations, for instance, the combing or parting of the hair in separate strands while thinning and shaping the hair, and for lifting separate strands of the hair while cutting and thinning the same without holding the ends of the hair in the lifted strands, and consequently making it possible to thin and shape the hair in very thin layers.

A further object of my invention is, to provide a hair cutting and shaping implement having a pair of double edged blades that cooperate with the combs, and said blades being mounted for reciprocating movement on the comb, and such movement being imparted by means of a trigger-like member that is pivotally mounted on the comb for convenient manipulation by the thumb of the hand that holds the implement.

With the foregoing and other objects in view my invention consists in certain novel features of construction and arrangements of parts that will be hereinafter more fully described and claimed and illustrated in the accompanying drawing in which:

Fig. 1 is a side elevational view of a hair cutting and shaping implement constructed in accordance with my invention.

Fig. 2 is an enlarged horizontal section taken on the line 2—2 of Fig. 1.

Fig. 3 is an enlarged cross-section taken on the line 3—3 of Fig. 1.

Fig. 4 is an elevational view of one of the double edged blades utilized in connection with the comb.

Fig. 5 is an elevational view of a portion of the implement with parts in section and showing one of the auxiliary combs applied thereto.

Fig. 6 is an elevational view of the attachment 10 that is provided with short hook-shaped teeth that are effective in lifting hair in separate strands during cutting and thinning operations.

Fig. 7 is an elevational view of a modified form of the implement wherein the blades are mounted 15 for reciprocating movement.

Fig. 8 is a horizontal section taken on the line 8—8 of Fig. 7.

Fig. 9 is a perspective view of a guard that may be detachably applied to the end of the implement for protecting the edges of the blades.

Referring by numerals to the accompanying drawing, and particularly to the construction illustrated in Figs. 1 to 6 inclusive, 10 designates a plate preferably formed of metal which forms the body of the implement, and a portion of one edge of this body is notched to form comb teeth 11 that may be utilized for ordinary hair combing operations. That portion of the edge of body 10 opposite the teeth 11 is preferably waved in shape as designated by 12, in order that the body of the implement may be more conveniently grasped and held in the hand, and formed on the side faces of the body between the teeth 11 and waved edge 12 are longitudinally disposed ribs 13 that re-inforce the body and enable the same to be more conveniently grasped and handled.

Formed on the edge of the body 10 with the waved portion 12 is a series of comb teeth 14 that are somewhat shorter than the teeth 11, and formed on the edge of the body opposite from these teeth 14 is a series of comb teeth 15 that are shorter than said teeth 14.

Formed through body 10 between the rows of teeth 14 and 15, is a pair of apertures 16, and removably positioned on the side faces of the body between the teeth 14 and 15 are double edged blades 17, each having a pair of apertures 18 that coincide with the apertures 16. Hinged to lugs 19 that project from the sides of the body 10 adjacent the inner ends of the ribs 13 and the row of comb teeth 11, are blade-clamping members 20 that extend lengthwise of the longitudinal surfaces of said blades, and formed integral with one of these members, is a pair of pins 21 that 55

are adapted to pass through the coinciding apertures 16 and 18 in the body 10 and blades 17, and the ends of these pins enter recesses 22 that are formed in the opposite one of the members 20.

5 Screw-seated in the end of the blade-clamping member 20 that is provided with the recesses 22, is a screw 23 provided on its outer end with a small head 24, and the point of this screw is adapted to enter a recess 25 that is formed in the adjacent one of the pins 21, thereby securely fastening the blade-clamping members 20 in closed positions.

10 Formed in the inner face of the blade-clamping member 20 that carries the screw 23, is a pair of grooves 26 that are adapted to receive pins that project from the back of auxiliary combs and hair-lifting members.

15 In Fig. 5 I have shown a portion of the implement turned upside down from the position as illustrated in Fig. 1, and applied to the side of the implement below the blade-clamping member 20 that carries screw 23 and overlying the lower portion of the face of the blade that is clamped by said member is an auxiliary comb 27, the teeth 25 of which are longer than the teeth 15, and the teeth of this auxiliary comb project a substantial distance beyond the ends of said teeth 15.

20 Projecting from the edge of the back of this auxiliary comb are pins 28 of resilient metal that are slightly curved lengthwise, and which pins are inserted in the grooves 26 in the blade-clamping member 20.

25 Due to the curvature of these pins 28 and the resiliency of the metal forming said pins, the auxiliary blade will be firmly held by the blade-clamping member when said pins are inserted in the grooves.

30 In Fig. 6 I have illustrated a plate 29 provided on its lower edge with a series of small, curved hooks 30 that are adapted to engage and lift the hair in separate small strands during hair cutting and thinning operations, thus making it possible to shape the hair in very thin layers without the necessity for lifting and holding the ends of the hair with the hands.

35 Projecting from the edge of this plate 29 opposite the edge provided with the hooks 30, are fingers 31 of resilient metal, which fingers are slightly curved lengthwise so that when they are inserted in the grooves 26, the plate 29 will be retained in position upon the implement.

40 In Figs. 7 and 8 I have illustrated a modified construction, wherein the blades are mounted for reciprocating movement on the body of the comb. In this construction, a plate 32 forms the body of the implement, and formed along approximately one-half of one edge of said plate is a series of ordinary comb teeth 33. Formed along the remaining portion of this edge of the plate is a series of comb teeth 34 that are much shorter than the teeth 33, and formed along the edge of the plate opposite from the teeth 34 is a series of comb teeth 35 that are somewhat shorter than said teeth 34. Formed through the plate 32 between the teeth 34 and 35 are short longitudinally disposed slots 36, and positioned against the side faces of the comb body 32 between the teeth 34 and 35 are double edged blades 37, the same being provided with apertures 38 that register with the slots 36. Applied to the outer faces of the double edged blades are blade-retaining plates 39, and formed integral with one of these plates is a pair of pins 40 that pass through the apertures 38 in blades, and the slots 36 in the comb body. The free ends of these pins project through apertures

41 formed in the opposite one of the blade-retaining plates, and formed through the ends of these pins are apertures 42.

5 A retaining pin or key 43 of resilient metal passes through the apertures 42 in the projecting ends of the pins 40 to secure the parts in assembled relation, and one end of this pin or key is provided with a depending hook 44 that may be conveniently engaged to withdraw the pin or key from the apertures in the pins 40 when it becomes necessary to disassemble the associated parts; for instance, when effecting an interchange of blades, or when the blades and combs are cleansed.

10 Formed in the inner face of the one of the retaining plates 39 adjacent the end thereof, is a recess 45 that receives a stud 46 formed on the end of a short pitman 47, and the outer end of this pitman is pivotally connected to the lower end of a trigger 48, the latter being pivotally mounted on the comb body 32. In Fig. 9, I have 15 illustrated a guard 50 having a channel-shaped member preferably formed of this sheet metal, and which guard is shaped so as to receive the end of the implement that carries the blades, and thus when said guard is applied to the implement, 20 the edges of the blades and the ends of the comb teeth adjacent the edges of said blades are covered and protected.

25 By using a pair of double edged blades on the implement, two cutting edges are associated with the teeth 14, and likewise two cutting edges are 30 associated with the comb teeth 15.

35 Such arrangement of material increases the effectiveness of the implement, and brings about a material saving of time and labor in the hair cutting and shaping and contouring operations. The comb teeth 14, which are slightly longer than the teeth 15, are utilized for thinning and shaping the hair by drawing the teeth of the comb through the hair away from the head and the comb teeth 15, and associated edges of the blades are utilized 40 for close thinning of the hair and for the shaving of hair from the face and neck.

45 The auxiliary comb 27 may be attached to the implement and used in combing the hair or the parting of the hair in separate strands when thinning and shaping the hair, thus eliminating the necessity for turning the comb end to end so as to bring the comb teeth 11 into use.

50 Plate 29 provided with the hook shaped teeth 30 is applied to the implement when it is desired to lift the hair in separate strands during the cutting and thinning operations, thus making it possible to thin and shape the hair in very thin layers.

55 Inasmuch as all parts of the implement are composed of metal, said implement may be very readily sterilized, or in the event that it becomes necessary to cleanse the blades and the combs with which the edges of said blades cooperate, 60 the blade-retaining members may be easily and quickly released so as to permit the blades to be detached from the implement.

65 In the modified construction illustrated in Figs. 7 and 8, the end of the implement having the comb teeth 33 is held in the hand and by rocking the trigger 48 on its axis, the blades will be reciprocated so that the edges of said blades travel past the teeth 34 and 35 first in one direction, and then in the other, so as to cooperate with 70 said teeth in quickly and effectively performing the hair cutting, thinning and contouring operations.

75 Thus it will be seen that I have provided a hair cutting and shaping implement that is relatively 75

simple in construction, inexpensive of manufacture and very effective in performing the functions for which it is intended.

It will be understood that minor changes in the size, forms and construction of the various parts of my improved hair cutting and shaping implement may be made and substituted for those herein shown and described without departing from the spirit of my invention, the scope of which is set forth in the appended claims.

What I claim as my invention:

1. In a hair cutting and shaping implement, an elongated substantially flat plate comprising a comb body and a handle, a series of conventional comb teeth formed along both edges of said comb body, comb teeth formed on one edge of the handle portion of said plate, a pair of double-edged blades detachably applied to the side faces of said comb body with the edges of said blades positioned adjacent said oppositely disposed sets of comb teeth and blade clamping members hinged at one end to the end of said comb body for holding the blades against said comb body.

2. In a hair cutting and shaping implement, an elongated substantially flat plate comprising a comb body and a handle, a series of conventional comb teeth formed along both edges of said comb body, comb teeth formed on one edge of the handle portion of said plate, one set of said comb teeth being longer than the other, a pair of double-edged blades detachably applied to the side faces of said body with the edges of said blades positioned adjacent said oppositely disposed sets of comb teeth and blade clamping members hinged at one end to the end of said

comb body for holding the blades against said comb body.

3. The combination with a comb body having two sets of teeth projecting in opposite directions, of double-edged blades positioned on the side faces of the comb body with the edges of said blades positioned adjacent the teeth of said combs, a handle projecting from one end of said comb body, comb teeth formed along one edge of said handle, said comb body and blades having registering apertures, blade clamping members hinged to one end of said comb body, studs projecting from one of said clamping members and adapted to pass through the apertures in said blades and clamping members and means for securing the free ends of said clamping members to each other and to the comb body.

4. The combination with a comb body having two sets of teeth projecting in opposite directions, one set of said comb teeth being longer than the other, of double-edged blades positioned on the side faces of the comb body with the edges of said blades positioned adjacent the teeth of said combs, a handle projecting from one end of said comb body, comb teeth formed along one edge of said handle, said comb body and blades having registering apertures, blade clamping members hinged to one end of said comb body, studs projecting from one of said clamping members and adapted to pass through the apertures in said blades and clamping members and means for securing one of said studs to one of the clamping members for maintaining both clamping members in blade clamping positions.

ARTHUR H. MADORE. 35
